OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP BEAM FOR LOOMS.

Application filed April 7, 1926. Serial No. 190,409.

This invention relates to improvements in warp beams for looms and it is the general object of the invention to provide such a beam with false heads which shall be quickly adjustable from one position to another and positively held in any adjusted position.

In certain looms, such for instance as those for weaving silk, the warp beam is provided with friction drums at the ends thereof and also false heads located intermediate the drums, the space between the heads being occupied by the warp. It is desirable that a loom should be capable of weaving cloth of varying widths between given limits and the false heads must accordingly be adjustable as to position in order to accommodate warps of varying widths. It is a further object of my invention to accomplish this result and provide means for holding the false heads and the barrel of the beam in fixed relation by cooperating parts so formed that the yarn will be permitted to lie properly on the barrel.

It is a more detailed object of my invention to provide the body of the barrel with a series of diagonal slots to cooperate with a multiple threaded worm gear rotatably mounted on some part of the false head so arranged that it can be tightened with respect to the head to prevent longitudinal motion of the false heads along the barrel. The diagonal slots are formed with their bottoms other than concentric with the axis of the barrel so as to resist angular motion of the false heads when the worm gear is tight. When loosened the worm permits free sliding movement of the false heads along the barrel but prevents angular motion relatively to the barrel.

It is a more detailed object of the invention to dispose the diagonal slots of the barrel so that a warp thread wrapped on the barrel and lying in a plane perpendicular to the axis thereof will be held out of contact with the bottom of the slots and will extend from one side thereof across the opening to the opposite side so as to lie along a very short chord of the circumference of the beam barrel.

With these and other objects in view which

will appear as the description proceeds, my invention resides in the combination and arrangement of parts hereinafter described and set forth in the claims.

In the accompanying drawings wherein I have shown a convenient embodiment of my invention,

Fig. 1 is a rear elevation of a warp beam made according to my present invention,

Fig. 2 is an end elevation taken in the direction of arrow 2, Fig. 1, and showing part of the loom and the beam as connected with a form of let-off frequently used on silk looms,

Fig. 3 is a vertical section on line 3—3 of Fig. 2, omitting the loom side and showing a portion of the barrel in elevation,

Fig. 4 is a perspective view of one of the false heads looking from the adjacent end of the beam,

Fig. 5 is a detail section on line 5—5 of Fig. 3, and

Fig. 6 is a detail top plan looking in the direction of arrow 6, Fig. 3, and showing the disposition of the slots in the barrel.

Referring particularly to Figs. 1 and 2 it will be seen that I have provided a loom stand indicated at 10 having a bearing 11 receiving the end 12 of a shaft 13 which extends through the beam B. It is to be so understood that there is a bearing 11 at each side of the loom and that the ends 12 are free to rotate in the bearings except as resisted by a weighted cord 14 anchored as at 15 to the frame of the loom and connected to weights W at the other end thereof. Said cord passes around a friction drum 16 one of which is located at each end of the beam to determine the tension of the yarn during the weaving process.

Each drum 16 is provided with a hub 17 to receive the adjacent end of a steel tube or barrel 18, each drum being provided with a web 19 perforated as at 20 to pass the threaded portion 21 of the shaft 13. A nut 22 on each threaded portion bears against the web 19 and when the nuts at each end are tightened the drums will be held against the barrel. Relative rotation of the drums with respect to the barrel is prevented by a lock-

ing screw 23 which passes through the hub 17 and into the barrel 18. A pin 24 may be provided to prevent the loss of the nut 22. The drums are located one at each end of 5 the beam and are substantially the same.

The false heads 30 to which my invention more particularly relates provide a face 31 which is finished accurately and is adapted to receive the end threads of the warp. 10 Each false head is provided with a hub 32 which extends along the barrel 18 a sufficient distance to hold the face 31 perpendicular to the axis of the barrel. Said hub 32 is recessed as at 33, see Fig. 4, and the hub is 15 further provided with an extension 34 into which extends a screw 35. Mounted for rotation on the screw is a worm gear 36 having one surface in contact with the head of the screw 35 and having the opposite surface in contact with the bottom of the 20 recess 33 and the extension 34.

As shown more particularly in Figs. 4 and 6 the barrel 18 is provided with a series of 25 diagonally disposed slots 40 the bottoms of which are perfectly flat. Said slots are not formed as part of a screw thread but have their bottoms tangent to a circle concentric with the axis of the barrel 18 so that the 30 ends of said slots 40 are farther from the center of the beam than the central portions of the bottoms of said slots. The angle of the slots 40 and the pitch of the threads on worm gear 36 are such that the teeth of the 35 worm will fit into the slots 40. I have shown the slots at one end of the barrel of opposite hand from those at the other end, and have shown the worm gears of opposite hand also, but I do not wish to be limited to this construction.

Under normal conditions with a given width of warp space between the false heads 30 the screw 35 will be tightened so as to prevent relative movement of the worm gear 36 with respect to the head. For this reason 45 the head is held against longitudinal motion along the barrel by engagement of the teeth of the worm gear with the walls of the slot 40 and angular or rotary movement of the heads on the barrel is prevented by the fact 50 that as the worm tends to turn about the axis of the barrel the teeth thereof will engage the bottoms of the slots, and as the latter are inclined outwardly from a circle tangent to the lowest part of the slot the 55 worm gear and hence the false head cannot turn about the axis of the barrel.

When it is desired to change the position of either head the bolt 35 corresponding thereto will be loosened and the head moved 60 by hand to the proper position, the pitch of the teeth on the gear 36 being steep enough to cause the same to rotate freely without offering undue resistance to the sliding movement of the false head. When the 65 heads 30 are in their adjusted position the

screws 35 may be tightened after which said heads will be held in fixed relation with respect to the barrel of the beam.

From the foregoing it will be seen that I have provided a warp beam having a false head which is movable quickly from one position to another and is held against undesirable longitudinal and angular motion with respect to the head by means of a clamping device so arranged as to have 70 positive contact with some portion of the barrel at all times but movable to permit ready adjustment of the false head with respect to the beam. It will also be noted that the angle of the slots 40 is such that a 75 warp thread lying in a plane perpendicular to the axis of the barrel 18 will not engage the bottoms of the slots but will pass from one edge to the other thereof and be almost concentric with the axis of the beam. While 80 I have shown the slots with flat bottoms to prevent relative angular motion of the head and barrel, yet the spiral teeth and diagonal grooves of themselves tend to prevent this motion, the diagonal line along which the 85 teeth and grooves coact having two perpendicular components which act to prevent both longitudinal as well as angular relative movement between the head and barrel.

Having thus described my invention it 90 will be apparent that changes and modifications may be made therein by those skilled in the art without departing from the spirit and scope of the invention, and I do not wish to be limited to the details herein disclosed, but what I claim is:

1. A warp beam for looms, said beam having a barrel, a false head slidably mounted on the barrel, and devices to lock the head with respect to the barrel including 105 a rotatable worm gear on the head having portions to enter diagonally disposed grooves in the barrel, said worm gear portions and grooves cooperating to prevent longitudinal and angular relative movement 110 of the head and barrel.

2. In a warp beam for looms, said beam having a barrel, a false head slideable along the barrel, a rotatable worm gear mounted on the false head having portions to engage 115 diagonal grooves formed in the barrel, and means to tighten the worm with respect to the head to prevent relative motion of the worm gear with respect to the head, said worm gear portions and grooves cooperating 120 to prevent longitudinal and angular relative movement of the head and barrel.

3. In a warp beam for looms, said beam having a barrel, a false head movable along the barrel, a worm gear mounted on the 125 false head for rotary movement with respect thereto, said barrel having diagonally disposed slots therein to receive the teeth of the gear, the bottoms of the slots being other than concentric with respect to the axis of 130

the beam, and means to prevent rotation of the worm with respect to the head, said worm gear teeth and slots cooperating to prevent longitudinal and angular relative movement of the head and barrel.

4. A warp beam for looms, said beam having a barrel, a false head slideable along the barrel, a worm gear mounted on the false head for rotation with respect thereto, said barrel being provided with diagonally disposed grooves to receive portions of the worm gear, said grooves being formed so that the bottoms thereof are substantially flat, and means to prevent rotation of the worm with respect to the false head, said worm gear portions and grooves cooperating to prevent longitudinal and angular relative movement of the head and barrel.

5. In a warp beam for looms, a barrel, a false head slideable along the barrel, a member mounted on the false head for rotation with respect thereto, said member having the periphery thereof formed with projections diagonally disposed with respect to the axis thereof, said barrel being provided with a plurality of diagonally disposed grooves the bottom of each groove being other than concentric with respect to the axis of the beam, said grooves to receive the projections of the member, and means to prevent rotary

movement of said member with respect to the false head, said projections and diagonal grooves cooperating to prevent angular as well as longitudinal relative movement of the head and barrel.

6. In a warp beam for looms, a barrel for the beam, a false head slideable on the barrel, and a member on the head mounted for rotation about an axis substantially parallel to the axis of the barrel and having portions to enter grooves formed in the barrel to prevent relative movement of the false head and barrel, said worm gear portions and grooves cooperating to prevent longitudinal and angular relative movement of the head and barrel.

7. In a warp beam for looms, a barrel for the beam, a false head slideable on the barrel, a member on the head mounted for rotation about an axis substantially parallel to the axis of the barrel and having portions to enter diagonal grooves formed in the barrel to prevent longitudinal and angular relative movement of the false head and barrel, and means to lock the member with respect to the false head.

In testimony whereof I have hereunto affixed my signature.

OSCAR V. PAYNE.
